United States Patent

Des. 234,564
Patented Mar. 25, 1975

234,564

COUNTER DIVIDER

David M. Moore, Pittsburgh, Pa., assignor to Armstrong
Store Fixtures Corp., Pittsburgh, Pa.

Filed Mar. 5, 1973, Ser. No. 338,094

Term of patent 14 years

Int. Cl. D6—06

U.S. Cl. D6—193

FIG. 1 is a front, top and right side perspective view of a counter divider showing my new design; and FIG. 2 is a right side elevational view.

I claim:

The ornamental design for a counter divider, as shown and described.
